UNITED STATES PATENT OFFICE.

JOHN B. BOLTON, OF NEW BEDFORD, MASSACHUSETTS, ASSIGNOR TO DRAPER COMPANY,
OF HOPEDALE, MASSACHUSETTS, A CORPORATION.

DOBBY MECHANISM FOR LENO-WEAVING.

No. 861,945.

Specification of Letters Patent.

Patented July 30, 1907.

Application filed October 17, 1906. Serial No. 339,381.

To all whom it may concern:

Be it known that I, JOHN B. BOLTON, a citizen of the United States, residing at New Bedford, in the county of Bristol and the State of Massachusetts, have invented 5 a new and useful Improvement in Dobby Mechanism for Leno-Weaving, of which the following is a specification.

This invention relates to a loom attachment and comprises a two part jack, half of which continues the full 10 length of the throw while the other half returns.

One of the objects of the invention is to obtain the requisite half and return motion without the aid of gears and cranks.

A further object of my invention is a device that will 15 also weave a leno top warp.

My invention consists in the novel features of construction and combination of parts hereinafter described, particularly pointed out in the claims and shown in the accompanying drawings, in which:—

20 Figure 1 is an elevation showing attached to a loom my improvement, certain positions of the lever being shown in dotted lines. Fig. 2 is a detail view, in elevation, of my improvement, detached. Fig. 3 is a perspective view of the jack. Fig. 4 is a perspective 25 detail view of a link, and, Fig. 5 is a perspective view of a trip segment.

In these drawings A represents the dobby frame of a loom having my improved leno motion attached thereto. From a suitable harness frame B a cord B' extends 30 over a pulley B² and is connected to the harness lever C by means of the usual form of loop C'. My improved jack is shown in detail in Fig. 3 and comprises the bar D having formed thereon on one side, and intermediate its ends a web D'. A circular boss D² is formed on the 35 bar or jack D and also extends over the web D', intermediate the ends of the same, the boss being situated equi-distant from the ends of the jack D. The boss D² is provided with a suitable bore D³ into which projects a suitable stud from the harness lever C, to which the 40 jack may be pinned or held in any suitable manner. The jack is provided with perforations, D⁴, D⁵, above and below the boss D², and the web D' is also perforated as shown at D⁶. I further provide two link arms E, identical in construction, perforated adjacent each 45 end, and also perforated adjacent the lower end, the end perforations being shown at E' and the third perforation being shown at E². These arms are placed in reverse position, one of them being pivotally connected to the web D' above the boss D², and the other arm

50 having an end pivotally connected to the web D' below the boss D². Curved segments F pivotally connect the arms E to the jack D, one end of the segments being pivoted directly to the jack, the pivot pins fitting in the perforations D⁴, D⁵, and the outer ends of the

segments F are pivotally connected to short links F' 55 which in turn have their other ends pivotally connected to the respective link arms E at E². As stated above the arms are arranged in a reverse position so that the link F' is pivoted to the lower of the arms E at a greater distance from the pivotal connection of 60 that arm to the web D', than the pivotal point E² and the pivotal point of the web D' on the upper arm E. Each of the segments F has formed thereon an angular projection F², adapted to be engaged by a fixed, spring tripping finger G. A flat, compound curved spring H 65 is arranged substantially parallel to the web D' and intermediate its ends bears on the boss D², while the ends of the spring bear on the upper arm E adjacent the pivotal connection of that arm and the link F', and the opposite end of the spring H bears on the arm E below 70 the boss D² adjacent the pivotal point of that arm and the web D'.

In Fig. 1 I have shown two dotted positions numbered respectively 1 and 2, said positions being taken by the harness lever, position 1 being the position occupied by the lever with the ordinary jack, and the full line position and dotted position number 2 being the 75 positions taken by the said lever with my improved form of jack.

The ends of the arms E, opposite the ends pivotally 80 connected to the web D', are connected to the usual hook members K. In this construction the reciprocating movement of the hooks are imparted to the jack through the medium of the link arms E. At the end of the half movement the tripping finger G is disengaged from the segment, the action of the two fingers being the same, and the jack is permitted to divide as a whole, the arm connected to the hook K continuing out the full length of the throw, while the bar D forming the jack proper reverses its movement and returns. 85 It will be understood that the arms E are parts of the jack, and are locked to the jack bar D, as shown in the lower portion of Fig. 2, when the tripper finger G is in engagement with the projection F². It will be understood that the free hook end of the tripping finger G, is 90 always in engagement with its segment F and rides upon the projection F², which lifts the tripping finger, there being as above stated, a separate finger for each of the segments.

Having thus fully described my invention what I 100 claim as new and desire to secure by Letters Patent is:

1. In a dobby mechanism adapted for leno weaving, the jack, the link arms pivotally connected thereto, means for normally pressing the links to the jack curved segments pivotally connected to the jack, and links pivotally connecting the segments to the link arms. 105

2. In a dobby mechanism adapted for leno weaving a jack, link arms pivotally connected thereto, segments pivotally connected to the jack, links pivotally connecting the

segments and the link arms, means for locking the arm to the jack during the first half of the jack movement, and a spring adapted to engage the link arms, as and for the purpose set forth.

5. A loom attachment of the kind described comprising a jack, pivoted arms carried thereby, segments carried by the jack and having angular projections, tripping fingers adapted to engage said projections through a portion of the travel of the segments, links connecting the segments and the arms, and a spring bearing at its ends on the arms, as and for the purpose specified.

10. In a dobby mechanism adapted for leno weaving a jack, link arms pivoted thereto, hooks pivoted to the arms,

curved segments having projections formed thereon and pivoted to the jack, a link connecting one segment to one arm adjacent the pivotal point of the arm to the jack, a link connecting the other segment to the remaining arm adjacent the pivotal point of the said arm and its hook member, tripping fingers adapted to engage the projections on the segments, and a spring adapted to engage the link 20 arms, substantially as set forth.

JOHN B. BOLTON.
